UNITED STATES PATENT OFFICE

154,361

DESIGN FOR A PAIR OF SPECTACLES

Carl C. Barbour, Houston, Tex.

Application February 15, 1949, Serial No. 875

Term of patent 14 years

(Cl. D57—1)

To all whom it may concern:

Be it known that I, Carl C. Barbour, a citizen of the United States, residing at Houston, in the county of Harris and State of Texas, have invented a new, original, and ornamental Design for a Pair of Spectacles, of which the following is a specification, reference being had to the accompanying drawings forming a part thereof.

Figure 1 is a front elevational view of a pair of spectacles, showing my new design;

Figure 2 is a top plan view;

Figure 3 is an end view.

The essential features of my design reside in the parts shown in full lines.

I claim:

The ornamental design for a pair of spectacles, as shown and described.

CARL C. BARBOUR.
